UNITED STATES PATENT OFFICE

105,778

DESIGN FOR AN ELECTRIC WAFFLE IRON OR THE LIKE

Edward S. Preston, Hinsdale, Ill., assignor to Chicago Electric Manufacturing Company,
Chicago, Ill., a corporation of Illinois

Application January 23, 1937, Serial No. 67,247

Term of patent 7 years

To all whom it may concern:

Be it known that I, Edward S. Preston, a citizen of the United States, residing at Hinsdale, in the county of Du Page and State of Illinois, have invented a new, original, and ornamental Design for an Electric Waffle Iron or the like, of which the following is a specification, reference being had to the accompanying drawings, forming part thereof:

In the drawings, Fig. 1 is a top plan view of an electric waffle iron embodying my design.

Fig. 2 is a side elevation of the same, looking upward from the bottom of Fig. 1.

Fig. 3 is an end elevation of the same as viewed from the right-hand side of Fig. 1.

I claim:

The ornamental design for an electric waffle iron or the like, substantially as shown.

EDWARD S. PRESTON.
